A. W. HILSINGER

PAPER BOX GUIDING AND CONVEYING MECHANISM

Filed June 30, 1922

Inventor

Adin W. Hilsinger

By his Attorney
Theodore H. Hilsinger

UNITED STATES PATENT OFFICE.

ADIN W. HILSINGER, OF ORANGE, NEW JERSEY, ASSIGNOR TO HENRY BRADY, INC., A CORPORATION OF NEW JERSEY.

PAPER-BOX GUIDING AND CONVEYING MECHANISM.

Application filed June 30, 1922. Serial No. 572,095.

My invention relates to improvements in conveying mechanism and more particularly has reference to such mechanism in a machine for making paper trays or boxes, having reference to means in combination with said machine for conveying away the formed boxes or trays for stacking, packing, counting, and other purposes.

In the accompanying drawing I have illustrated in Fig. 1 in perspective, parts being broken away, parts of a box making machine embodying an application of my invention; Fig. 2 is an end view of a box in the guides, and Fig. 3 is an end view partly in section illustrating the conveyer.

2 indicates the frame of the machine and 3 a tray formed therein and ready to be fed leftwardly out of the machine. At opposite sides of the formed tray and beneath the forming plunger not shown are pivotally mounted guides as 5-5'. Each of these guides is pivotally mounted upon a shaft 6 having a lever 7 pivotally connected at 8 to one end of a rod 9 which is pivoted at opposite end to a rod 10 pivoted at 11, and at the opposite end of the rod 10 is pivotally mounted a vertical rod 12, the lower end of which is pivotally mounted to the lever 13 which is pivotally mounted at 14 to the frame of the machine, and which is provided with a roller 15 riding upon the cam 16 so that as the shaft 17 rotates, the guides 5-5' approach and recede from the path of the box or tray 3, the roller 15 being kept upon the cam 16 by the action of the spring 18 as shown. In this manner the guides 5-5' are withdrawn from the path of the plunger during the forming operation and as the plunger lifts approach one another beneath the plunger serving as rail guides for the tray as it travels leftwardly.

These guides when in their guiding position are in effect continuations of the rails 20-20' which continue to guide the tray as it leaves the machine, and for the purpose of carrying the tray along leftwardly between the guides, endless chains 21 are provided which pass over the sprockets 22, 23 and 24, said endless chains being provided at intervals with brackets 25 carrying cross bars 26 which engage the right end of the tray such as 3 carrying it leftward until it is deposited beyond the apron or slide 27.

Of course it will be understood that various modifications may be made in the construction and arrangement of parts without departing from the spirit of the invention as claimed.

I claim:

1. In a machine of the class described, a conveyer for successively engaging and feeding articles therethrough, and guide rails on pivotally mounted axes parallel with the line of feed, said rails adapted to move in a path transverse to the line of feed for guiding said boxes and cam mechanism for the purpose of moving said guide rails toward and from each other.

2. In a machine of the class described, a conveyer for successively engaging and feeding articles therethrough, and guide rails on pivotally mounted axes parallel with the line of feed cam mechanism, said rails adapted by said cam mechanism to move in a path transverse to the line of feed for guiding said boxes, said rails adapted to engage said boxes at the sides above and inside the flared edges thereof, thereby preventing the lifting of said boxes.

In testimony whereof I hereunto affix my signature.

ADIN W. HILSINGER.
